PAGE 2

Fig. 2.

Fig. 3.

Fig. 4.

Fig. 5.

FIG. 1 is a top plan view of a lavatory showing my new design.

FIG. 2 is a front elevational view thereof.

FIG. 3 is a rear elevational view thereof.

FIG. 4 is a side elevational view thereof.

FIG. 5 is a cross-sectional view taken on line 5—5 of FIG. 2.

The characteristic feature of my design resides in the graining striations all radiating outwardly from the center waste outlet of the lavatory towards the outer periphery of the lavatory.

I claim:

The ornamental design for a lavatory or similar article, as shown and described.
